(57) **CLAIM**

The ornamental design for a pair of axle mounted pedal straps, as shown and described.

DESCRIPTION

This design application is co-pending with utility application Ser. No. 16/150,671 filed Oct. 3, 2018, which is incorporated herein by reference in its entirety.

FIG. 1 is a front perspective view of a pair of axle mounted pedal straps fitted to pedals shown with dotted lines; FIG. 2 is a top plan view of the left member of my new design;

FIG. 3 is a bottom plan view of the right member of my new design;

FIG. 4 is a right side elevation view of the right member of my new design;

FIG. 5 is a left side elevation view of the right member of my new design;

FIG. 6 is a front elevation view of the right member of my new design;

FIG. 7 is a rear elevation view of the right member of my new design;

FIG. 8 is a rear top perspective view of the right member of my new design with a pedal shown in dots;

FIG. 9 is a rear top perspective view of the right member of my new design without the pedal;

FIG. 10 is a rear elevation view of the right member of my new design;

FIG. 11 is a left side elevation view of the right member of my new design;

FIG. 12 is a bottom plan view of the right member of my new design;

FIG. 13 is a top plan view of the right member of my new design with pedal shown in dotted lines;

FIG. 14 is a bottom plan view of the left member of my new design with pedal shown in dotted lines;

FIG. 15 is a right side elevation view of the left member of my new design with pedal shown in dotted lines;

FIG. 16 is a left side elevation view of the left member of my new design with pedal shown in dotted lines;

FIG. 17 is a front elevation view of the left member of my new design with pedal shown in dotted lines;

(Continued)

FIG. 18 is a rear elevation view of the left member of my new design;

FIG. 19 is a rear top perspective view of the left member of my new design with pedal shown in dotted lines;

FIG. 20 is a rear top perspective view of the left member without the pedal;

FIG. 21 is a rear elevation view of the left member of my new design without the pedal;

FIG. 22 is a left side elevation view of the left member of my new design without the pedal; and,

FIG. 23 is a bottom plan view of the left member of my new design without the pedal.

The broken lines in the drawings illustrate portions of the pedal straps and environmental pedals, axles, and mounting holes that form no part of the claimed design.
